BUILDING

Charles R. Turner, Hopkins, Mo. (½ Advance Concrete
& Asphalt Co., P.O. Box 324, Maryville, Mo. 64468)

Continuation-in-part of abandoned design application Ser.
No. 116,296, Feb. 17, 1971. This application May 21,
1973, Ser. No. 362,477

Term of patent 14 years

Int. Cl. D25—03

U.S. Cl. D13—1 E

Fig. 1.

Fig. 2.

Fig. 3.

FIG. 1 is a plan view of a building showing my new design;

FIG. 2 is a side elevational view of the building; the remaining two sides being substantially the same as that shown; and

FIG. 3 is a side elevational view of a building showing a second embodiment of my new design, the remaining two sides being substantially the same as that shown, and the plan view thereof being the same as shown in FIG. 1.

This is a continuation-in-part of design application Ser. No. 116,296, filed Feb. 17, 1971, and now abandoned.

I claim:

The ornamental design for a building, as shown and described.
